Fig. 1

Fig. 2

FIG. 1 is a view in perspective of the pitcher, showing my new design.

FIG. 2 is a view in side elevation of the pitcher of FIG. 1.

The characteristic feature of my design resides in the particular configuration of the pouring lip in combination with a horizontal continuous bead spaced therefrom and a handle of the particular configuration shown whose upper terminus is spaced below the horizontal bead.

I claim:

The ornamental design for a pitcher or similar article, substantially as shown and described.
